UNITED STATES PATENT OFFICE.

LUDWIG KOFFMAHNE, OF BERLIN-CHARLOTTENBURG, GERMANY, ASSIGNOR TO SIEMENS-SCHUCKERTWERKE G. M. B. H., OF SIEMENSSTADT, NEAR BERLIN, GERMANY, A CORPORATION OF GERMANY.

GRINDING APPARATUS.

1,185,105.

Specification of Letters Patent.

Patented May 30, 1916.

Application filed April 30, 1914. Serial No. 835,516.

To all whom it may concern:

Be it known that I, LUDWIG KOFFMAHNE, a German citizen, and resident of Berlin-Charlottenburg, Germany, have invented certain new and useful Improvements in Grinding Apparatus, of which the following is a specification.

This invention more particularly relates to an improvement of the ordinary devices for smooth grinding of the curvilinear faces of profiled grinder disks, which serve for the finishing of the teeth of cog wheels after their formation by the milling process and the subsequent hardening. In devices of this kind the working tools, which are preferably provided with diamond points, are mounted to permit their points to oscillate to and fro either in a straight or in a curved line. The points of the working tools are further swung by a simultaneous change of the pivot distance by a templet which slides upon a guiding member, thus determining the curvilinear motion of the points of the grinding tools along the faces of the grinding disk.

This invention relates more specifically to a construction whereby the templet is immediately fixed to the fulcrum pin or also to the diamond holder without the insertion of intermediate movable parts, said templet during motion of said pin being carried along a fixed guiding member, so that a swinging of the working tools takes place in the intended curved line of the face of the tooth. Obviously also the templet may be arranged fixed in a space and the stop may be connected with the rotating axles of the working tools, and slide upon the templet by positively swinging with said working tools.

By the new arrangement according to this invention I attain an essentially more accurate working than that which is possible by the ordinary devices of this kind, since by my invention the disadvantage is obviated that the touch between the stop and the templet and the swinging of the working tools due to the idle motion of the intermediate member are displaced in time against each other. If however, the time displacement between said touch and said swinging is done away with, the distortion of the curve described by the point of the grinding tool will be obviated, and the one motion

becomes the exact mirror image of the other. 55 Because of this one will be enabled to enhance the accuracy of working by the employment of very large templets which in a construction in accordance to this invention may easily be given a very great ratio 60 of transmission between the working and the guiding side of the swinging tool holders.

My invention will be more fully understood by reference to the accompanying 65 drawing, of which Figure 1 shows an elevation of a device according to my present invention, and of which Fig. 2 is a plan view taken on Fig. 1, but with the work removed. Fig. 3 is a detail view.

The construction shown in the drawing may be regarded as an example of carrying my invention into effect, in which the tool-holder itself carries the templet, so that at the bench of the machine only a fixed stop 75 needs to be provided, along which the templet may slide.

In the drawing *a* designates the grinding tools, *b* the tool-holders and *i* the grinder disk which shall be worked upon. The tool-holders *b* are rotatably mounted at *c* in arms *d* which swing around the fulcrum pins *e*. The arms *d* and the tool-holders *b* with the templets *f* are pressed in any desired manner against the rollers *g*, the means of exerting such a pressure being indicated by the spring *s* in the drawing, which spring tends to approach the lower ends of the arms *d* to each other. The rollers *g* are mounted at a fixed point relatively to the 90 working bench *k*. If now the templets *f*, and therewith simultaneously the tool-holders *b* are rotated, the tool points are carried in a curve corresponding to the desired form of the faces *h* of the tooth. It is now immediately evident that in this arrangement, by choosing a great transmission ratio, the operation may be made as accurate as desired at the double-armed tool-holder. The templet of course is made, so that it may 100 easily be exchanged. In the drawing this templet is shown as a segment which is kept in position upon a disk *n* by means of the

s m, the disks being integral or rigidly joined with the arms *d*. The means for 105 periodically oscillating the arms *d* against the spring *s* comprise shafts *p* upon which the arms *d* are rigidly mounted. Shafts *p*

are journaled in the bed *q* on the work bench *k*. The shafts *p* may be automatically oscillated by connecting them through suitable mechanisms with the drive shaft of the machine, but preferably this is done by hand, means being shown in Figs. 2 and 3. The shafts *p* carry cams *t* on which are mounted pins *u*. The links *z*¹ and *z*² are pivotally connected with pins *u* at one end and at their other ends are joined together and with the lever *z*³ by the pivot *y*.

While I have shown in the drawing a construction, in which the tool-holders are mounted to exert a swinging motion, it is of course understood that this motion may as well be a sliding motion.

I claim as new and desire to secure by Letters Patent of the United States:—

1. An apparatus of the character described, comprising a pair of pointed grinding tools, tool-holders therefor, said tool-holders being mounted to permit curvilinear motion of the points of said tools, pressure means applied to said tool-holders tending to move the points of said tools away from each other, segmental templets mounted directly upon said tool-holders, and stops for said templets counteracting said pressure means, whereby the points of said grinding tools will be enabled to move according to the curve prescribed by the form of said templets.

2. An apparatus of the character described, comprising a pair of pointed grinding tools, a double-armed lever mechanism

for mounting said grinding tools to permit motion of the points thereof according to a desired curve, pressure means applied to said lever mechanism, stops adapted to guide templets carried by said lever mechanism, said stops counteracting said pressure means by the contact with said templets, whereby the points of said grinding tools will be permitted to move in a curve which is positively prescribed by the form of said templets.

3. An apparatus of the character described, comprising a pair of pointed grinding tools mounted with their points opposite to each other, a pair of double lever mechanisms respectively carrying said grinding tools and permitting curvilinear motion of the points of said tools in a plane, pressure means applied to said double lever mechanism, segmental templets exchangeably mounted directly on said mechanism, and guiding members for said templets, said guiding members being adapted to counteract said pressure means, whereby the points of said grinding tools will be permitted to move along a curve which is positively prescribed by the form of said templets.

In witness whereof I have hereunto set my signature in the presence of two subscribing witnesses:

LUDWIG KOFFMAHNE.
